Primary Examiner — Christian P. McLean*Assistant Examiner* — Nader Abadir(74) *Attorney, Agent, or Firm* — McAndrews, Held & Malloy, Ltd.(57) **CLAIM**

The ornamental design for an eating utensil, as shown and described.

DESCRIPTION

FIG. 1 is top and front perspective view of an eating utensil showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view;

FIG. 7 is a bottom plan view; and,

FIG. 8 is a bottom and rear perspective view thereof.

The dashed broken lines in the figures illustrate portions of the eating utensil that form no part of the claimed design.

1 Claim, 7 Drawing Sheets(56)
